(57) **CLAIM**

The ornamental design for a light for digital camera, as shown and described.

DESCRIPTION

FIG. 1 is a top front perspective view of a light for digital camera;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is another front perspective view thereof being combined with a digital camera;

FIG. 9 is another right side view thereof being combined with a digital camera;

FIG. 10 is another right side view thereof showing a first state, in which the light is rotated by 90 degrees

FIG. 11 is another right side view thereof showing a second state, in which the light is rotated vertically; and,

FIG. 12 is another top view thereof showing a third state, in which the light is horizontally rotated with respect to a digital camera.

The broken lines shown in the drawings are directed to environment and are for illustrative purpose only; the broken lines form no part of the claimed design.
